UNITED STATES PATENT OFFICE.

KARL L. HEERRMANN, OF DETROIT, MICHIGAN, ASSIGNOR TO THE STUDEBAKER CORPORATION, OF SOUTH BEND, INDIANA, A CORPORATION OF NEW JERSEY.

METHOD OF PATCHING LEATHER.

Application filed April 8, 1925. Serial No. 21,712.

This invention relates to the patching of leather and has for its objects the providing of a form of patch that when finished will not be detectable, which will provide means whereby patched leather will be as strong as unpatched leather as far as practical uses are concerned, which for practical results may be used for any purpose that unpatched leather may be used for, and which will be economical and practical to use.

Up to the present time, so far as I am aware, there has been no practical method of patching cuts, gouges, scratches or digs in the surface of a piece of leather so that it may be used in any place or for any use that unpatched leather may be used in or for. I am aware that shoe makers have patched holes or ruptures extending clear through a piece of leather by cementing and sewing another piece of leather to the back of each piece over such hole or rupture, but this method produces an extra thickness of material at the point of patching and does not entirely conceal such hole or rupture, and is not used where the hole or rupture does not extend clear through the piece. An improvement on such method is set forth in my co-pending patent application on "patching leather", filed July 18, 1923, Serial Number 654,480.

The advantages of providing an undetectable patch for such a cut, gouge, scratch or dig is particularly apparent in connection with upholstery leather, which leather is commonly of split skin and usually coat-finished on its grain or naturally outward side. Where such a piece of leather is needed for an automobile cushion, for instance, it is preferably in one piece and of such a size as will take one-half of the ordinary sized hide, and it must be uniformly free from surface defects and of uniform strength. Where such a piece of leather, in the past, has had a cut, gouge, etc., in its outer surface of a size to be apparent after finishing, it has been necessary to cut out a strip across the width of the piece in which such cut or gouge is embodied, and sew the acceptable parts together, taking care that the seam thus formed will fall in one of the folds of the leather between the panels of the cushion. Where there are two such cuts or gouges in a single piece, the strips of ma-

terial cut out must be of such a width that both seams fall in the folds of the cushion panels, and in such a case it is evident that there is a substantial loss of leather. Due to this loss and to the expense of cutting and sewing, the natural result is that hides having such defects sell for a substantially less amount than perfect hides, and are more or less of a loss to their owners.

Having the above in mind, it is the principal object of the present invention to provide a method for eliminating such apparent defects as are above referred to whereby such leather may be used for any practical purposes that leather not having such defects may be used, and such method consists of mechanically removing from a piece of leather containing such a gouge, cut, etc., a smaller piece of leather therefrom of a predetermined size and shape, about, and in which is located, such gouge or cut. The piece of leather thus being removed is preferably of less thickness than the thickness of the leather from which it is removed so that the depression caused by its removal does not extend through the normal thickness of the leather, the removing of such piece of leather being accomplished by a mechanical skiving operation whereby the depression formed thereby is very shallow and gradually tapering from the edges to the bottom at a very small angle. A patch, which has also been formed by a mechanical skiving operation to the exact size and shape of the depression, is then inserted in the mechanically formed depression and cementitiously secured therein. This patch is so broadly bonded in the depression that the leather is freely bendable or distortable without liability of squeezing or working the patch out of place by flexure of the patched portion of the leather during the wear and strains of use. After such patch has been applied the leather may be finished if desirable or necessary and if the leather is to be used for upholstery purposes it may be coated and grained in the conventional manner, thereby concealing any trace of the patch or previous cut, gouge, etc.

It is important that the edge of the patch be thin and regular or free from irregularities, as must also be the surfaces of the depression, because if they are present, pits or

trough-like conditions will be present at the junction of the edge with the skin and thereby form smaller depressions around the edges of the patch in whole or in part with the result that very frequently a graining board used in the grain finishing operations will pull the patch out of place.

The above being among the objects of the present invention, the same consists of certain features of construction and combination of parts to be hereinafter described, with reference to the accompanying drawing, and then claimed, having the above and other objects in view.

15 In the accompanying drawing which illustrates a suitable embodiment of the present invention, and in which like numerals refer to like parts throughout the several different views,

20 Figure 1 is a plan view of a piece of leather having a gouge in its surface as previously described.

Figure 2 is a sectional view of the piece of leather taken on the line 2—2 of Figure 1.

25 Figure 3 is a plan view of the same piece of leather as in the previous views, showing the portion which formerly included the gouge cut away to provide a seat for a patch, the former position of the gouge being indicated by dotted lines.

30 Figure 4 is a sectional view of the piece of leather taken on the line 4—4 of Figure 3, as prepared to receive a patch, the former position of the gouge being indicated by dotted lines.

35 Figure 5 is a plan view of a patch which has been prepared for the depression formed by cutting away the leather about and including the gouge.

40 Figure 6 is a section of the patch taken on the line 6—6 of Figure 5.

45 Figure 7 is a sectional view taken through the center of the patch of the piece of leather and the patch shown in the previous views after they have been cementitiously joined or bonded together in the manner prescribed.

50 Figure 8 is a sectional view corresponding to Figure 7 but in which a conventional coat finish has been applied over the normally exposed surface thereof.

55 Figure 9 is a side elevation of a machine which may be conveniently employed for skiving out both the depression in the leather and the patch therefor.

Figure 10 is a view of the cutting mechanism of the machine of Figure 9 taken from below the same and looking upward.

60 Figure 11 is a sectional view of the cutting mechanism shown in Figure 10, taken on the line 11—11 of Figure 10.

65 In the drawings is shown a piece of leather 15 which has a gouge 16 in its surface, which gouge extends to such an extent into the leather, but not all the way through it, that

if it were not possible to conceal it by properly patching it, it would necessitate the rejection of such piece of leather for upholstery uses, particularly if it were situated on the face side thereof. It is, of course, understood that the thickness of the leather shown is greatly exaggerated to more clearly describe the invention, such pieces of leather being, in ordinary practice, much thinner and much more flexible. The patching of such gouge 16 is preferably accomplished after splitting of the hide and before finishing the same, so that the operation of working down the split or finishing it will substantially, if not entirely, eliminate any outward signs of the same.

The gouge 16, as shown in Figures 1 and 2, is prepared, as shown in Figures 3 and 4, for patching by removing a certain amount of the leather about, and in which is included, the gouge 16. The leather so removed is preferably of a predetermined size and shape, which is readily accomplished and made practically possible by means of the machine herein later described, to form a very shallow depression 17 the sides of which extend from the edges of such depression to the bottom of the same at a very slight, flat angle. The prepared depression 17 is cemented or otherwise suitably secured in matching relation with a patch 18, which is formed from a piece of leather in exactly the same manner as the depression 17 is formed, and which is of exactly the same size, shape and dimensions as the depression 17. Inasmuch as the patch 18 is of the same size and shape as the depression 17, it will be apparent that upper and lower surfaces converge at its edges at a very slight angle, giving it, in effect, a feather edge, and providing, with the complementary opposed surface of the leather which forms the depression 17, a maximum of bonding surface between the two. This large bonding surface coupled with the thin flexible marginal edges of the patch insures that bending or flexing of the leather at the point of patching will not loosen the patch, nor will it cause the leather at this point to be noticeably stiff or unyielding, and in addition, such patched portion I have found to be of equal strength to any unpatched portion of the leather.

When such patch is applied to the normally unexposed and unfinished side of the leather it is difficult to locate such a patched portion even without any subsequent finishing operation, and when it is located on the normally exposed surface and is subsequently finished, particularly if a finish coat of peroxilin or other coating material such as 19 is applied and grained, it is impossible to distinguish the patch, and in such a case such a patched piece of leather may be used for any practical purposes that an unpatched

piece may be used for, thereby effecting considerable saving of leather and money.

In order to facilitate such patching and to make the same practical, economical, and to place it on a so-called production basis, it is desirable to form such depressions as previously described to one of a number of standard or set sizes and contours and to provide standard patches to fit such standard depressions. In such an event the patches and depressions may be prepared separately and at different times and places if so desired, and in the operation of patching the leather the patch may be applied to any corresponding depression in the leather with an assurance that it will fit perfectly.

To realize such a condition it is necessary to provide means for forming uniform patches and uniformly preparing the depressions in the leather to correspond therewith. Although there are several methods that might be employed for this purpose, I have illustrated in Figures 9, 10 and 11 one particular machine with which this may be readily, easily and accurately accomplished, and which machine is the subject of my copending patent application on "Machine for cutting patches and the like" filed April 14, 1924, Serial Number 706,433. This machine is such that any number of patches may be made, or depressions formed, to duplicate a standard or fixed size of patch or depression, and is such that a smooth and unbroken matching surface of such patch or depression is obtained and previously described as being necessary.

This machine is composed of a base member 20 having an upright post 21 which supports and upon which is swiveled an arm 22 which journals and supports the cutting apparatus or head. A nut 23 threaded on the post 21 below the arm 22 provides vertical adjustment of the arm 22 and therefore of the cutting head.

The removal of the leather about and including the gouge 16, as shown, may be accomplished by a number of different means including sanding or grinding, or cutting with a knife or other edge. In the machine illustrated in the drawing a knife edge is used and the method employed is to support a button such as 24 on the base 20 directly under the cutting head, place the leather at the point where the depression is to be formed, or the patch is to be formed, directly over the button, draw the leather down in close relationship with the button and pass the knife horizontally across it in the required close proximity to it. The button 24 is so shaped on its upper surface, against which the leather rests, as to correspond to the exact shape of the depression to be formed, or the patch to be cut out, and it will be evident that when the leather is drawn down tightly over the top of the but-

ton and a knife is passed horizontally over the button in relatively close but spaced relation thereto, all the leather above the horizontal plane of knife edge will be removed, and this removed portion will be identical in shape, when either its upper or lower surface is positioned flat in one plane, to the upper corresponding surface of the button, and also, that when the piece of leather from which such piece has been removed is positioned flat, the depression formed by such removal will be exactly complementary to the top surface of the button and to either surface of the piece removed, or patch, when the opposite surface of such patch is flat. It will be further evident that by this method any number of such depressions or any number of patches, both of which are formed by exactly the same operation, may be formed to exactly the same size, shape, contour and dimensions.

While I have shown in the drawings a button 24 having a spherical top surface, which accordingly causes circular depressions and patches to be formed in the cutting operation, it will be evident that such top surface may be changed in size, shape, contour and dimensions to agree with any size, shape, contour and dimensions of depression or patch which it may be desired to form, such as in case of a patch for a relatively long and narrow knife cut, a long narrow button may be used. If such a cut is too long for the dimensions of the machine to form a patch for it in one operation, separate parts of it may be patched in successive operations until the whole is patched.

I have found that if a knife is passed over the button directly from one side of it to the other, the knife has a tendency to lift the leather after it has passed over the center of the button 24, thereby causing the depression 17 or patch 18 which is being prepared to not exactly match the upper surface of the button 24 as desired, but has the effect of digging into the leather 15 on passing over the center of the button which results in a sharper angle to that side of the depression or patch as the case may be. I have found that by revolving the knife, so as to begin cutting around the periphery of the depression or patch, and gradually bringing it in to the center of the button 24 in a spiral movement, a depression 17 or patch 18 results which corresponds exactly to the upper surface of the button 24, and the so cut surface of the depression or patch is smooth and free from any waves or other imperfections.

In the machine shown in the drawing a cutting head is provided with mechanism to revolve the knife and to draw it to the center as above described. This cutting head is supported on the swiveled arm 22 and has a vertical shaft 25 journaled in and supported

by the arm 22, a crank or handle 26 being secured to its upper end for the purpose of operating it, and an arm 27 being secured to its lower end. A knife supporting member 28 is pivoted at 29 to the arm 27 to swing in a horizontal plane and is provided with a detachable knife blade 30, the center of which is preferably on an arc of a circle whose center is at 29 and which also passes through the axial line of the shaft 25. A track member 31 whose lower face is in a horizontal plane is non-rotatably secured to the lower face of the outer end of the arm 22 about the shaft 25 and above the arm 27 and knife supporting member 28. A spiral T-shaped groove or track 32 is cut in the lower face of the track member 28 as shown in Figures 10 and 11. A pin or finger 33, secured to the member 28 adjacent the knife blade 30 and extending upwardly therefrom engages the groove 32, and may be either merely guided therein or may also serve to help support the member 28 by reason of its head portion engaging the head portion of the T-groove. It will be evident that the pin 33 engaging the groove 32 controls the position of the knife blade 30 in relation to the center of the button 24 when the arm 22 is swung over to bring the cutting head directly over the button 24, or, in other words, when the axis of the shaft 25 and the axis of the button 24 are in line. It will also be apparent that when the handle 26 is turned or rotated, causing the arm 27, member 28 and knife blade 30 to turn therewith, the knife blade 30 will be caused to move outwardly or inwardly from or to the axis of the shaft 25, and consequently the button 24 when in the position above referred to, in a manner corresponding to the direction in which the handle is turned, thus causing the knife blade 30 to have a rotary motion about as well as a transverse movement to or from the center of the button 24. This movement, it has been found, results in a depression or patch that perfectly matches the button 24 and gives a clean, even, cut surface. For this reason the machine particularly lends itself to patching leather in the manner above described.

In the operation of preparing a piece of leather having such a gouge or similar defect as 16 for patching by the machine illustrated and described, the handle 26 is first revolved to cause the knife blade 30 to move to its extreme outward position, the arm 22 being then swung around the post 21 to carry the cutting head away from its position over the button 24, the leather 15 is placed over the button 24 with the gouge 16 directly over the top surface of the button 24 and facing upwardly, the leather 15 being then drawn down tightly against the upper surface of the button 24 by a ring (not shown) or other suitable means, the arm 22

is swung back to bring the axis of the shaft 25 in line with the axis of the button 24, and the handle 26 is rotated to cause the blade 30 to rotate around and to approach the center of the button 24, thereby removing the leather about and including the gouge 16 and forming the depression as at 17. In identically the same manner, and by identically the same operations, a piece of leather having a perfect surface may be placed over the button 24 and a portion removed therefrom, such removed portion in the case of a piece of leather having a perfect surface, providing a patch 18 for the depression 17 as previously described.

While in the above description reference has been made solely to the patching of leather, it will be understood that the process is equally applicable to other materials capable of like uses, and the term "leather" in both the specification and the claims is meant to include all materials of this nature.

Formal changes may be made in the specific embodiment of the invention described, without departing from the spirit and substance of the broad invention, the scope of which is commensurate with the appended claims.

What I claim is:—

1. The process of filling in imperfections in the surface of a sheet of leather which consists in mechanically removing a portion of the material about and including said imperfection to form a relatively shallow depression having gradually sloping side walls, in mechanically forming a patch from a body of similar material and of substantially the same area, contour, and sloping complementary surface as the said depression, in cementitiously securing said patch in said depression in matching relation therewith, and in finally finishing said leather to completely cover the same including said patch.

2. The process of filling in imperfections in the surface of a sheet of leather, which consists in first mechanically removing a portion of such material of a predetermined size, shape and contour about and in which is included said imperfection to form a shallow depression having gradually tapering side walls and a substantially flat bottom wall, in mechanically forming a patch from a body of similar material and of substantially the same size, shape and contour of the said depression, and in finally applying to and cementitiously securing said patch in said depression.

3. The process of filling in imperfections in the surface of a sheet of leather which consists of mechanically cutting away said material about and including said imperfection to form a depression in the surface of said material of predetermined area and contour and having widely divergent tapered side

walls and a substantially flat bottom wall, in preparing a patch having a complementary tapered edge and of substantially the same area and configuration as that of said depression and in applying said tapered edge patch to said depression and securing the same therein to said bottom and side walls,

thereby to present a substantially flush outer surface of the patch and the patched material.

Signed by me at Detroit, Michigan, U. S. A., this 2nd day of April 1925.

KARL L. HERRMANN.
